UNITED STATES PATENT OFFICE.

HALVER R. STRAIGHT, OF ADEL, IOWA.

PALLET-FEEDING MECHANISM.

Application filed June 1, 1925. Serial No. 34,054.

To all whom it may concern:

Be it known that I, HALVER R. STRAIGHT, a citizen of the United States, and a resident of Adel, in the county of Dallas and State 5 of Iowa, have invented a certain new and useful Pallet-Feeding Mechanism, of which the following is a specification.

The object of my invention is to provide a mechanism of simple, durable and inexpensive construction, which may be used in connection with a tile cutter and off-bearing mechanism, for the purpose of automatically feeding pallets in operative relation with the off-bearing mechanism, so as to 10 receive the ware from said mechanism in such a manner that the ware may be automatically delivered to said pallets and placed thereon in proper relation to said pallet and to each other.

20 A further object is to provide in connection with a tile cutter and off-bearing mechanism improved means for feeding pallets into position for receiving tile from said off-bearing mechanism, said device including 25 means for timing the off-bearing mechanism and the pallet feeding mechanism from the said tile cutter.

My invention consists in the construction, arrangement and combination of the various 30 parts of the device, whereby the objects contemplated are attained, as hereinafter more fully set forth, pointed out in my claims, and illustrated in the accompanying drawings, in which:

35 Figure 1 is a side elevation of my improved device with the front side of the supporting frame removed.

Figure 2 is a detail sectional view taken 40 on the line 2—2 of Figure 1.

Figure 3 is a detail sectional view taken 45 on the line 3—3 of Figure 1.

Figure 4 is a detail sectional view taken 50 on the line 4—4 of Figure 1.

Figure 5 is a detail, side elevation of a 55 portion of the pallet feeding mechanism; and

Figure 6 is a detail sectional view taken 60 on the line 6—6 of Figure 5.

The numeral 10 indicates a supporting 65 frame of one form of a tile cutter which is in common use, and which employs a rotary cutting member 11 provided with cutting wires 12. Said member 11 is driven through pinions 13 and bevel gears 14 and 15. The 70 pinions 13 are mounted on a shaft 16 driven

through a belt 17. The cutting member 11 may be provided with one or more wires 12 depending on the length of the blocks to be cut.

It will be seen that the number of revolutions of the shaft 16 bears a fixed ratio with the number of blocks or tile cut to each revolution of the gears 14 and 15, and for that reason the shaft 16 may be employed as a driving medium for my improved mechanism, which will not only impart the necessary power for operating the device, but also may be utilized to time the said mechanism with the blocks or tile which are severed from the continuously moving 70 column of clay 18. These tile are designated by the numeral 19. Said tile are delivered to the upper run of a continuously moving conveyor 20, said run being supported by rollers 21 mounted in a suitable 75 frame 22. The conveyor 20 is mounted on suitable rollers 23 and 24, the roller 24 being provided with a shaft 25, one end of which is provided with a sprocket wheel 26.

Mounted adjacent to the delivery end of the conveyor 20 is an off-bearing mechanism which is indicated generally by the numeral 27, having the main operating shaft 28. The outer end of the shaft 28 is provided with a sprocket wheel 29. The sprocket wheels 26 and 29 are designed to carry a chain 30 driven from a sprocket 31 secured to the shaft 32. The inner end of the shaft 32 is provided with a beveled gear 33 in mesh with a beveled pinion 34, said pinion being mounted on a shaft 35 and having at its opposite end a sprocket 36. Said sprocket 36 is designed to carry a chain 37 carried by a sprocket 38 on the outer end of the shaft 16.

By this arrangement it will be seen that I have provided means whereby the conveyor 20 and the off-bearing mechanism 27 may be simultaneously operated, and which are timed with the tile cutter. The off-bearing mechanism is of a type such as described in my co-pending application filed May 22, 1923, Serial Number 640,658, and which is not described in detail herein due to the fact that it forms no particular part of my present invention.

This off-bearing mechanism, however, is provided with a delivery arm 39 which is adapted to receive the blocks 19 from the conveyor 20 and deliver them to a point 110

near its bottom side in a vertical position to a continuously operating conveyor, as disclosed in my previous application. My present invention pertains to a mechanism which is substituted for the continuously operating conveyor and adapted to feed a series of pallets, which are designated by the numeral 40, to substantially the same position as occupied by the delivery conveyor of said off-bearing mechanism, which consists of a frame 41 comprising a series of upright supports 42. The frame 41 includes side members between which is mounted a series of transversely arranged shafts 43 provided with rollers 44 which are for the purpose of supporting the pallets 40. Each of the pallets 40 comprises a pair of angle irons 45 spaced apart and connected by means of cross members 46, said cross members having their lower edges provided with a flat portion 47 and at each end a beveled portion 48. The upper edge of the members 46 is curved slightly to permit longitudinally extending slats 49 to be mounted thereon in such a manner that the upper edges of the slats 49 will be level with the upper edges of the angles 45. Said slats 49 and the upper surface of said angles provide footing for the blocks 19, which are designed to be supported in an upright position thereon, as clearly illustrated in Figure 1.

It will be seen by referring to Figure 4 that the lower edges of the angles 45 are designed to travel on the upper surface of the rollers 44, said rollers being provided with flanges 50 to form guides to prevent lateral movement of the pallets as they are advanced. The frame 41 and the rollers 44 are so located that one of the pallets will be made to rest immediately beneath the off-bearing mechanism, as clearly illustrated in Figure 1.

For intermittently advancing the said pallets relative to the off-bearing mechanism, I have provided a rock shaft 51 beneath the frame 41. Said rock shaft 51 is provided with an upwardly extending rock arm 52 to which is connected a horizontally arranged link 53 which is connected to a slide bar 54 and designed to move longitudinally beneath the frame 41. Said slide bar has guide members 55 mounted between rollers 56. Each end of said bar 54 is provided with a spring actuated dog 57 which dogs are designed to engage the side members of the angles 45 in such a manner that as the bar 54 is moved rearwardly, the pallet 40 will also be moved rearwardly an equal distance. The dogs 57 are so arranged that as the bar 54 is moved forwardly, they will slide over the surface of said angle irons 45. Said bar 54 is actuated when the shaft 51 is rocked, which is accomplished by means of a crank 58

mounted on the outer end of the shaft 51, which is connected to a rod 59 operated from the wrist pin 60, see Figure 5. Said wrist pin 60 is adjustably mounted in a slot 61 of a disk 62 which is carried and supported by the sprocket wheel 31.

The said disk 62 is provided with a graduated scale 63 while the pin 60 is provided with a pointer 64. By this arrangement it will be seen I have provided means whereby the length of the stroke of the bar 54 may be varied by simply adjusting the wrist pin toward or from the center of the disk 62, as it will readily be seen that it is necessary to adjust the stroke of the bar 54, due to the fact that the blocks 19 are of various sizes. A large block requires a long stroke, while a smaller block requires a shorter stroke. The spaces between the blocks are about the same, regardless of the size of said blocks.

Thus it will be seen that each time a block is delivered from the off-bearing mechanism to the pallet 40, the said pallet is advanced a distance equal to the width of said block plus the space between the blocks. The shaft 32 being driven from the shaft 16 will automatically time the feeding of the pallets with the off-bearing mechanism.

For supplying additional pallets I have provided a transversely arranged conveyor 65 which consists simply of an inclined chute having side members 66. The lower end of the chute is designed to receive the pallets in parallel relation with the pallets being fed beneath the off-bearing mechanism. The inclination of the chute is such that the said pallets will be fed by gravity. The lower end of said chute is of such elevation that one pallet will be permitted to rest on the rollers 44, while a second pallet may be slid to position on top of the first pallet. The inclined portion of the lower edges of the members 46 permit the top pallet to slide into position laterally on top of the one beneath. The rear end of the upper one of said pallets is moved on top of the forward end of the first one of said pallets in a manner somewhat as illustrated in Figure 1. When the said lower pallet has been fed forwardly to such an extent that its rear end is slightly over half way from under the pallet above, the rear end of the second pallet will rest on and engage a pair of friction rollers 67, said rollers being driven preferably at a speed greater than the maximum speed of the intermittently moving pallet, as this will cause the said second pallet to have a tendency to be advanced forwardly, but which is prevented by means of a stop bar 68, which is arranged at the forward end of said pallet. Said second pallet may be retained in this position until the lower one of said pallets has been fed from beneath the said forward end of the second pallet, which will then permit the second

100
105
110
115
120

130

pallet to rest on the rollers 44 in alinement with the feeding dogs 57.

It will be seen that inasmuch as the said dogs 57 are intermittently operated, the rear end of the first pallet will be advanced ahead of the forward end of the second or upper pallet, before said upper pallet has time to fall into position on the rollers 44. This will leave a space between the ends of 10 said pallets, which will be closed on account of the feeding tendency of the roller 67. Said roller 67 may be continuously operated if so desired through a chain 69 mounted on a sprocket 70, said sprocket 70 being carried 15 by a shaft 71 on which the said roller 67 is mounted. The chain 69 is driven by means of a sprocket 72 and bevel gears 73 and a shaft 74. Said shaft 74 may be either continuously or intermittently operated. If it 20 is intermittently operated in unison with the movements of the bar 54, the speed of the roller 67 should be slightly greater than the maximum speed of the bar 54, while if the said roller 67 is continuously operated, the 25 speed should be such that the second pallet will be caused to engage the end of the first pallet before the actuating dogs 57 engage said second pallet. This is necessary in order to give the proper spacing between the 30 ends of the pallets and the first block mounted thereon, so as to prevent a single block from being mounted on two adjacent pallets at the same time.

For supporting the pallet which is being 35 loaded against rearward movement as the actuating bar 54 is moved rearwardly through the frictional contacts of the dogs 57, I have provided a pair of stationary dogs 75.

By this arrangement it will be seen I 40 have provided a mechanism which is adapted to be used in connection with a tile cutter, and its off-bearing mechanism, in such a manner that pallets may be fed beneath the off-bearing mechanism in an intermittent manner, the stroke of which may be varied to accommodate tile of various widths, and which is provided with an accumulating conveyor for supplying new 45 pallets as they are being filled. The said accumulating conveyor is arranged to automatically replace the said filled pallets. The device is also provided with means whereby the adjacent ends of the pallets may be 50 placed in contact before they are moved to position for receiving the ware from the off-bearing mechanism.

I claim as my invention:

1. In combination, a tile cutter, an off-bearing mechanism, a pallet accumulating device, means for receiving a pallet from said accumulating device and feeding it intermittently beneath the discharge end of said off-bearing mechanism.
- 65 2. In combination, a tile cutter, an off-

bearing mechanism, a pallet accumulating device, means for receiving a pallet from said said accumulating device and feeding it intermittently beneath the discharge end of said off-bearing mechanism, means for varying the length of the stroke of said intermittent feeding mechanism.

3. In combination, a tile cutter, an off-bearing mechanism, a pallet accumulating device, means for receiving a pallet from said accumulating device and feeding it intermittently beneath the discharge end of said off-bearing mechanism, means for varying the length of the stroke of said intermittent feeding mechanism, and means for timing said off-bearing mechanism and said pallet feeding mechanism with said tile cutter.

4. In a device of the class described, a supporting frame, a series of transversely arranged supporting rollers adapted to receive a pallet, said pallet having its edges formed parallel, gripping means movable longitudinally with said pallet for engaging its side edges and imparting movement intermittently thereto, and means for actuating said gripping mechanism.

5. In a device of the class described, a supporting frame, a series of transversely arranged supporting rollers adapted to receive a pallet, said pallet having its edges formed parallel, gripping means movable longitudinally with said pallet for engaging its side edges and imparting movement intermittently thereto, means for actuating said gripping mechanism, and means for varying the stroke of said gripping mechanism.

6. In a device of the class described, a supporting frame, a series of transversely arranged supporting rollers, adapted to receive a pallet, said pallet having its edges formed parallel, gripping means movable longitudinally with said pallet for engaging its side edges and imparting movement intermittently thereto, means for actuating said gripping mechanism, means for varying the stroke of said gripping mechanism, an inclined and transversely arranged accumulating conveyor having its delivery end adjacent to one side of said pallet and above said pallet so that a pallet arranged in said inclined conveyor may be delivered by gravity on top of the first said pallet, means for preventing forward movement of the second pallet as it rests on said first pallet until after the first pallet has been moved from beneath it, and means for feeding said second pallet into engagement with the rear end of said first pallet and into engagement with said gripping mechanism.

7. In a device of the class described, a supporting frame adapted to support a pallet, means for intermittently feeding said pallet, means for automatically feeding one

- end of said second pallet adjacent to the rear end of said first pallet as they pass through said intermittent feeding mechanism.
5. In a device of the class described, a supporting frame, a pallet conveyor, means for imparting intermittent movement to said pallet comprising a reciprocating bar, a pair of dogs on said bar for gripping the edges 10 of said pallet when said bar is moved in one direction, and for disengaging said bar when moved in the opposite direction, a second pair of gripping dogs mounted stationary to prevent movement of said pallet when 15 the said reciprocating bar is moved in one direction.
8. In a device of the class described, a supporting frame, a pallet conveyor, means for imparting intermittent movement to said pallet comprising a reciprocating bar, a pair of dogs on said bar for gripping the edges of said pallet when said bar is moved in one direction, and for disengaging said bar when moved in the opposite direction, a second pair of gripping dogs mounted stationary to prevent movement of said pallet when the said reciprocating bar is moved in 20 one direction, means for imparting reciprocating movement to said bar comprising a rock shaft, a rock arm, a link for connecting said rock arm with said bar, a second rock arm, a rotating crank, and a connecting rod for said crank and said second arm.
10. In a device of the class described, a supporting frame, a pallet conveyor, means for imparting intermittent movement to said pallet comprising a reciprocating bar, a pair of dogs on said bar for gripping the edges of said pallet when said bar is moved in one direction, and for disengaging said 30 bar when moved in the opposite direction, a second pair of gripping dogs mounted stationary to prevent movement of said pallet when the said reciprocating bar is moved in one direction, means for imparting reciprocating movement to said bar comprising a rock shaft, a rock arm, a link for connecting said rock arm with said bar, a second rock arm, a rotating crank, and a connecting rod for said crank and said second arm.
9. In a device of the class described, a supporting frame, a pallet conveyor, means for imparting intermittent movement to said pallet comprising a reciprocating bar, a pair of dogs on said bar for gripping the edges of said pallet when said bar is moved in one direction, and for disengaging said bar when moved in the opposite direction, a second pair of gripping dogs mounted stationary to prevent movement of said pallet when the said reciprocating bar is moved in 35 one direction, means for imparting reciprocating movement to said bar comprising a rock shaft, a rock arm, a link for connecting said rock arm with said bar, a second rock arm, a rotating crank, and a connecting rod for said crank and said second arm.
